M. O. SATHER

SHOWCASE

Filed Dec. 20, 1924

UNITED STATES PATENT OFFICE.

MARTIN O. SATHER, OF LUVERNE, MINNESOTA.

SHOW CASE.

Application filed December 20, 1924. Serial No. 757,243.

To all whom it may concern:

Be it known that I, MARTIN O. SATHER, a citizen of the United States, residing at Luverne, in the county of Rock and State of Minnesota, have invented certain new and useful Improvements in Show Cases, of which the following is a specification.

This invention relates to a show or display case designed primarily for displaying fruits and vegetables, but it is to be understood that a show case, in accordance with this invention, can be employed for any purposes for which it is found applicable, and the invention has for its object to provide, in a manner as hereinafter set forth, a show or display case including a plurality of independent compartments for receiving different articles of merchandise visible to a customer through a front transparent wall common to all of said compartments, and further providing the case, at its rear with means whereby access can be had independently to each compartment for removing the merchandise therefrom without disturbing the front display of the same until the entire contents of such compartment has been sold or removed.

A further object of the invention is to provide, in a manner as hereinafter set forth, a show or display case formed of a plurality of independent compartments, each having means to provide for independent access thereto and further with means to provide for the independent ventilation of each compartment when the latter is closed.

Further objects of the invention are to provide in a manner as hereinafter set forth, a show or display formed of a plurality of independent compartments and which is simple in its construction and arrangements, strong, durable, compartment, thoroughly efficient and convenient in its use, readily assembled and comparatively inexpensive to manufacture.

With the foregoing and other objects in view the invention consists of the novel construction, combination and arrangement of parts, as hereinafter more specifically described and illustrated in the accompanying drawing, wherein is shown an embodiment of the invention, but it is to be understood that changes, variations and modifications can be resorted to which fall within the scope of the claims herewith appended.

In the drawings wherein like reference

characters denote corresponding parts throughout the several views:

Figure 1, is a front elevation of a shoe or display case in accordance with this invention.

60

Figure 2, is a rear elevation thereof.

Figure 3, is a vertical sectional view.

Figure 4, is a section on line 4—4, Figure 1.

Figure 5, is a section on line 5—5, Figure 2.

Referring to the drawings in detail the case comprises a pair of vertically disposed side walls 1, 2 of substantial height, width and thickness and each of which has its inner face, near its forward edge, formed with a length wise extending groove 3.

Arranged between the walls 1, 2 and flush with the forward edges thereof, is a series of superposed combined spacing and retaining members.

The said members are secured, in any suitable manner to the wall 1, 2 as well as abut against the inner faces thereof. The said members further are spaced equi-distant with respect to each other, and the upper member of the series is indicated at 4, the lower member at 5, and the intermediate members at 6.

The member 4 is flush with the top edges of the walls 1, 2. The member 5 is of greater width than either of the other members of said series and depends below the bottom edges of the walls 1, 2, and said member 5 is rabbeted, as at 7, to provide a seat for a purpose to be presently referred to. The members 4 and 6 are of the same width.

Arranged between and secured to the walls 1, 2 is a series of superposed rectangular frames 8 and which are of less length than the width of such walls. The frames 8 are arranged equi-distant with respect to each other and the upper and lower frames of said series are flush respectively with the top and bottom edges of the walls 1, 2. The

upper frame opposes and is spaced from the member 4, the lower frame abuts against the inner face of the member 5 directly below the rabbet 7, and each of the other frames opposes and is spaced from a member 6.

The frames 8 are arranged rearwardly of the members 4, 5 and 6, and terminate at a point forwardly of the rear edges of the walls 1, 2.

The front wall of the case is indicated at 9, and which is constructed of a transparent panel mounted in the grooves 3, and seated

on the shoulder formed by the rabbet 7. The wall 9 has its top edge flush with the top edges of the wall 1, 2 and said wall 9, is interposed between the members 4, 5 and 6 and the frames 8, with the exception of the lower one of said frames 8.

The rear wall of the case includes a series of wide sections 10 and a series of narrow sections 10' and which are interposed between and secured to the side walls 1, 2. The sections are so arranged relatively to each other whereby a narrow section will be positioned above and spaced from a wide section and the upper section of the series of sections 10' has its top edge flush with the top edges of the walls 1, 2 and lowermost section 10 depends below the bottom edges of such walls and the depending portion of the said section 10 is flush with the member 5. The sections 10 and 10' abut against the rear end of the frames 8. The openings formed between the sections 10 and 10' are of rectangular contour and indicated at 11. Each of the sections 10 is provided centrally thereof with a rectangular opening 12.

The outer face of each section 10, directly below each opening 11, is cutaway lengthwise to provide a pair of opposed shoulders 13 and a pair of opposed shoulders 14. Each opening 12 is arranged between a pair of opposed shoulders 13. Secured to each pair of opposed shoulders 14 is a pair of opposed and spaced retaining strips 15, which in connection with a pair of opposed shoulders 13 provide a slide way 16 for a shiftable screen 17 normally in a position to oppose and partly close an opening 12.

The rear wall further includes a series of transparent doors or closures, each of which is indicated at 18, and arranged in an opening 11. Each door or closure is hinged at its top, as at 19, to a section 19'. A knob 20 is carried by each door or closure to facilitate the swinging thereof to open and shut position with respect to an opening 11.

Secured to the top of each of the frames 8, with the exception of the upper frame 8, is a rectangular partition, which abuts against the inner faces of the walls 1, 2 and extends from the front wall 9 to the rear wall of the case. Secured to the upper frame 8 and member 4, as well as to the top edges of the walls 1, 2, 9 and 10, is the top wall 21 which projects laterally from the said walls and member 4. The wall 21 is of rectangular contour.

Seven partitions are shown, but the number can be increased or diminished depending upon the number of independent compartments the case is to be provided with. The partitions are indicated at 22, 23, 24, 25, 26, 27 and 28 and each forms the bottom of a compartment. The compartments are indicated at 29, 30, 31, 32, 33, 34 and 35. The

front wall 9, side walls 1, 2, and rear wall 10 are common to the several compartments. The partitions 22, 23, 24, 25, 26 and 27 form respectively the tops of the compartments 30, 31, 32, 33, 34 and 35. The top wall 21 forms the top of the compartment 29. Each compartment has its rear formed with a shiftable closure 18 so that access can be had thereto to remove or supply merchandise thereto when occasion requires.

The openings 12, in connection with the screen 17 are provided for ventilating the compartments. The bottom wall of the openings 12 are flush with the upper face of the partitions, whereby when the screens are shifted clear of the openings 12, these latter can be used as clean outs for the compartments when desired.

Secured to the walls 1, 2, as well as to the member 5 and wall 10, are depending brackets 36, carrying rollers 37 to provide for the shifting of the case from place to place when desired.

By setting up the compartments in the manner as stated the merchandise in each compartment is visible to a customer, and further the merchandise can be removed from the compartment, at the rear thereof, without disturbing the front display thereof, furthermore each compartment includes means for ventilating the same when its respective closure is in closed position, and it is thought that the many advantages of a show or display case in accordance with this invention, can be readily understood, and although the preferred embodiment of the invention is as described and illustrated; yet changes in the details of construction can be had which will fall within the scope of the invention as claimed.

I claim:

1. A display case comprising a top, a pair of side walls, a one-piece transparent wall and a rear wall formed of a series of wide and a series of narrow sections alternately disposed with respect to and spaced from each other to provide openings, a series of shiftable closures for said openings hinged to said narrow sections, said narrow sections arranged above said wide sections, each of said wide sections provided with an opening, a series of slideable screens each mounted in a wide section, shiftable horizontally thereof and coacting with an opening in the wide section to provide a ventilator, means arranged between said walls to provide a plurality of superposed independent rectangular compartments, one of said closures and a ventilator arranged at the rear end of each compartment, and means carried by said wide sections for slidably connecting said screens therewith.

2. A display case comprising a top, a pair of side walls, a one-piece transparent wall and a rear wall formed of a series of wide

and a series of narrow sections alternately disposed with respect to and spaced from each other to provide openings, a series of shiftable closures for said openings hinged to said narrow sections, said narrow sections arranged above said wide sections, each of said wide sections provided with an opening, a series of slideable screens each mounted in a wide section, shiftable horizontally thereof and coacting with an opening in the wide section to provide a ventilator, means arranged between said walls to provide a plurality of superposed independent rectangular compartments, one of said

closures and a ventilator arranged at the rear end of each compartment, means carried by said wide sections for slidably connecting said screens therewith, and the bottom wall of each of the openings in the wide sections flush with the upper face of the bottom of each of said compartments to provide a clean-out opening for a compartment when a screen is shifted clear of its respective opening.

In testimony whereof, I affix my signature hereto.

MARTIN O. SATHER.
